UNITED STATES PATENT OFFICE

ELI M. GREENLEE, OF NEWPORT, KENTUCKY, ASSIGNOR OF ONE-FOURTH TO ORVILLE W. HOUSE, OF WILLIAMSPORT, OHIO, AND ONE-FOURTH TO HARRY H. COHEN, OF CINCINNATI, OHIO, AND ONE-HALF TO HARRY H. MARTIN, OF COVINGTON, KENTUCKY, AND GEORGE W. SHUEY, OF CINCINNATI, OHIO

TRAFFIC CONTROL DEVICE

Application filed November 18, 1931. Serial No. 575,866.

This invention relates to traffic control and is particularly directed to an improvement in traffic signal display devices of the type adapted to be placed on the street at the intersection of side streets with arterial highways, at railroad crossings, and arterial highway crossings, or any place in the street where a traffic signal is required. The devices are conventionally applied directly to the surface of the street and are located, in most instances, centrally of the width of the street for the passage of traffic at either side thereof and facing the traffic to be directed at a position for displaying to the motorist the desired words such as Stop, Slow, Danger, etc.

It is an object of this invention to provide an improved signal display device of the above described character which is of heavy rugged durable construction and which displays the traffic control insignia or warning at an angle considerably toward the upright, whereby it may be readily observed from a considerable distance by an approaching motorist, and to further provide that, in the event of the vehicle wheels being driven over the device from any angle, the display means will yield or collapse toward the plane of the street momentarily under the car tread without damage to the car or the traffic display device.

It is another object of this invention to provide a traffic signal display device of the described nature in which the mounting of the movable display element is extremely substantial and the shock of impact in case the device is struck by traffic is preferably taken up by the frame without undue stress or strain on the parts which might tend to break the device, and moreover to provide for this purpose that the collapsible or compressible display element is fully receivable within the confines of the frame.

It is a still further object to provide that other signals may be incorporated in the device for display in the direction opposite to the main signal.

Other objects and certain advantages will be more fully apparent from a description of the accompanying drawing, in which:

Figure 1 is a perspective view of the improved traffic control device.

Figure 2 is a sectional view taken on line 2-2, Figure 1, illustrating the mounting of the springs controlling the signal display element and the pivotal mounting of the display element.

Figure 3 is a front view of the device taken partly in section for illustrating the retaining pins for the display element.

Figure 4 is a sectional view taken similar to Figure 2, but showing the signal display element depressed under the tread of a motor vehicle.

The improvement, described in general, comprises, a stationary frame 5 adapted to be secured to the surface of the street and a movable signal display element 6 mounted in the frame and adapted to normally assume a position wherein the signal is readily visible and in the line of vision of the approaching motorist, and which element is free to assume a recumbent position not dangerously obstructive to the passage of a vehicle over the device.

The frame of the device is constructed so as to entirely receive the movable display element within its confines. The movable display element is pivoted at its forward edge within a recess 7 in the frame and depresses against springs 8, under the action of weight from above, to be received within the recess. The total height of the frame is not great, the purpose being to prevent any damage to the device or the car passing over the same in the event that a motorist should accidentally drive over the device.

The frame is cast of metal and is of ribbed construction internally. Attaching flanges 9 are included at the respective ends of the frame and these flanges are provided with countersunk apertures 10 for receiving anchorage means such as bolts 11 or any other fastening devices. The interior of the frame includes a centrally and transversely disposed vertical rib 12 and cross ribs 13 connecting the forward and rear margins of the frame to the central rib. The frame is inclined from a central point to each side for

eliminating any sharp or abrupt obstruction in the street.

At the forward side of the device and included within one sloping portion thereof, 5 the recess 7 is provided within which recess the signal display element 6 is mounted. The signal display element as to its general outline is of a size to fit snugly within the recess of the frame. Moreover, the signal display 10 element at all times including its normal display position remains in positions closing the recess whereby it is impossible for débris of any sort to lodge beneath the movable element and interfere with its operation.

15 The particular signal is cast in the face of the display element 6, the word Stop being included in the present illustration. The letters 14 of the word are sufficiently embossed or raised on the face of the element 20 for ready visibility at a great distance. To further accentuate the appearance of the signal, the tops of the letters may be chromium plated and the background or general surface of the display element or plate painted black.

25 The signal display element or plate includes a depending flange 15 at its rear edge and side flanges 16 as well as intermediate cross flanges 17 on its underside. This rear flange 15, side flanges 16 and cross flanges 17 30 are arranged to provide greater general thickness to the element at the rear edge with a considerable reduction toward the forward edge. A series of heavy lugs 18 are cast in the plate at its forward edge, these lugs functioning as pivots for the plate.

Within the recess of the frame and toward the forward portion thereof, where the cross ribs join the front margin of the frame, fillets 19 present curved surfaces. Lugs 20 are provided on the cross ribs adjacent the fillets 19, these lugs 20 having curved surfaces which with the curved surfaces of the lugs 19, provide semicircular pivot sockets or seats for receiving the pivot lugs 18 of the signal display plate or element.

For maintaining the signal display element against displacement from within the frame, a pin 21 is fixed in the frame at each end of the signal display element on the 50 axis of pivotal movement thereof. These pins extend into bores 22 in the signal display element. The bores 22 are of greater diameter than the pins and therefore afford sufficient clearance about the pins, whereby 55 the pivotal contact of the signal display element in its sockets is assured and there is no strain or shearing action on the retaining pins 21.

The springs 8 are mounted beneath the 60 stop element, one toward each end thereof within the recess and are suitably arranged and anchored for exerting an upward pressure on the swinging end of the signal display element. Each of these springs consists 65 of a length of spring wire having one end

23 anchored in an anchorage lug 24 rising from a cross rib and includes a coiled bight portion 25 intermediate its length providing the necessary flexibility and spring tension for the extended end 26 which bears against 70 the underside of the signal display element.

Each spring is maintained against lateral displacement at its forward or coiled end by means of a lug 27 adjacent a socket lug 20 of the frame, the coiled portion of 75 the spring fitting between these lugs. Normally the springs hold the signal display element in a position toward the vertical or at an obtuse angle relative to the surface of the street, the signal display element abutting the frame at this time as at 28. In the event that a vehicle wheel rides over the device, the stop element moves on its pivots, the shock being taken up in the sockets and the springs compressing to permit the signal display element to move fully into the recess. A set of bumpers are mounted in the frame for abutment by the swinging display element cushioning the shock imposed thereon when it is suddenly depressed. The bumpers are disclosed in the form of rubber buttons 29 secured on the cross ribs of the frame and engaged by the underside of the cross ribs of the swinging element.

In order to provide for signals which may be observed from the direction opposite to the display of the principal signal, a plate 30 may be attached and countersunk in the opposite sloping face of the frame by means of screws 31 as shown and may include any 100 signal word desired.

Having described my invention, I claim:

1. In a traffic control device, a frame, means for securing said frame to the surface of the street, said frame including a recess in the surface thereof, a plate mounted in said recess and including the signal to be displayed, said frame provided with pivot sockets, said plate having pivot lugs loosely seated in said pivot sockets for rocking movement therein for displaying the signal to the approaching motorist, means independent of the lug and socket connections for preventing displacement of the plate from its mounted position in said recess, said independent means normally out of contact with the plate, and springs for normally urging the plate upwardly on its pivot, said plate arranged relative to said recess whereby, upon the passage of a vehicle over the plate, 115 the plate will be depressed into the recess without damage thereto.

2. In a traffic control device, a frame, means for attaching the frame to the surface of the street, said frame including a recess in its upper surface, pivot sockets in said recess at the forward edge thereof, a signal display plate having the signal word on its front surface, said plate having its lower end pivotally engaged in said pivot sockets, 130

5 said plate including bores on its axis of pivotal movement, pins mounted in the frame and extending loosely into said bores, and springs normally urging the signal display plate into a position of pivotal movement toward an upright position.

3. A traffic signal device, comprising, a frame adapted to be secured to the surface of the street, said frame provided with a recess in its upper surface, a signal display element depressibly mounted in said recess, means for normally maintaining said signal display element in a position at an obtuse angle relative to the surface of the street, said signal display element closing the entrance to said recess at all times, and said recess adapted to fully receive said signal display element within its confines when said signal display element is engaged by traffic.

20 In witness whereof, I hereunto subscribe my name.

ELI M. GREENLEE.
